4 Claims. (Cl. 219—216)

The invention relates to an apparatus for producing photographic images and printing plates from a light-sensitive layer exposed to form an image and a transfer layer in which apparatus the layers are pressed together and are heated. Images of opposite gradations are produced in the light-sensitive layers and in the transfer layer: a negative image is produced in the light-sensitive layer and a non-laterally-reversed positive copy of the original to be reproduced is obtained in the transfer layer.

Examples of light-sensitive layers are silver halide emulsion layers which contain tanning developers. If these layers are heated after they are exposed to form an image, the exposed areas are hardened, while the unexposed areas are transferred to the transfer layer and serve to produce a positive image. In this way there are obtained relief images which can be used as printing plates. It is also possible to work with silver halide emulsion layers containing developer substances and with transfer layers which contain substances producing colored compounds with the developer substances. During heat development, the developer substances are transferred from the unexposed areas to the transfer layer and there converted by reaction with the substances contained there into color images. Those on the exposed areas have been used up for developing the exposed silver halide. Suitable materials for carrying out these processes are set out in German patent specifications No. 895,101, 1,003,577, 1,004,043 and 1,015,313 and in German Auslegeschrift 1,002,628.

The aforementioned patent specifications disclose the use of drying drums which can be heated electrically, to heat the layers and to press them together. In such apparatus, the papers are pressed, by means of a water-permeable cloth, onto a heated metal support. It has, however, been found that inconsistent results are obtained when using such apparatus.

Heat-copying apparatus is also known which comprise essentially an endless plastic band, which is guided over a plurality of guide rollers, and a heat radiator, which supplies by radiation the heat necessary to develop the image. The guiding means are such that the heat-sensitive paper and the original are pressed, one against the other, between the band and a guide pulley and are irradiated through the band. The copy is formed by image-wise heating of the heat-sensitive paper, initiating a reaction which blackens the paper. Apparatus of this type is not suitable for the aforementioned heat-development processes, since these require entirely different conditions.

It has now been found that these disadvantages may be avoided and that satisfactory results may be obtained by using apparatus in which the aforesaid layers are pressed together and heated by a heatable means having water-impermeable, pressure-tight surfaces.

These surfaces are, on the one side, part of the surface of a heated, rotatably mounted drum, and, on the other side, an endless band of water-tight, elastic material which is pressed on to the surface of the drum with the aid of guide rollers. The band-guiding means is, advantageously, so arranged that the temperature of that part of the band surface which comes into contact with the drum or the interposed photographic materials, after

2

having run over the guide rollers, is 20 to 70° C. lower than the temperature of the drum surface by cooling during travelling. The temperature of the drum is kept at 100 to 250° C., preferably at 120–150°, and is regulated by any conventional adjusting and maintaining device.

In order to produce satisfactory results, it is expedient to moisten the photographic materials with water before introducing them into the heating zone. For this purpose, there are used moistening cylinders which are so arranged that the photographic materials are moistened from the rear under pressure.

In the present invention the photographic materials to be processed in the present apparatus are pressed, one against the other, in a closed space with the simultaneous action of moisture; the steam formed from the moisture cannot escape outwardly, but is forced, under pressure, on to the photographic layers. With the heating presses and drying drums hitherto employed, these conditions could not be obtained, since a vapor-permeable and water-permeable cloth is used. It is, moreover, desirable for the developing process that there be a temperature drop of 20 to 70° C. perpendicular to the plane of the layers which are heated and pressed together.

25 The rotational speed of the heating drum is preferably so regulated that the photographic layers remain a few seconds, for example, 5 to 10 seconds, in the heating zone. The pressure exerted by the endless band on the heating drum is adjusted by means of adjustable guide rollers, preferably to 0.3 to 2 kg./cm.².

One embodiment of the apparatus according to the invention is shown diagrammatically in the accompanying drawing in which the apparatus consists of a drum 1 which can be heated electrically and against which an endless band 2 of temperature-resistant, elastic, water-impermeable and vapor-tight material of low heat conductivity is so pressed that it covers a part of the drum periphery, for example half, and almost the full width of the drum. The width of the band must also be greater than the width of the negative or positive material. A sealed development and transfer zone is then formed between the drum surface and the band by applying strong pressure to the band.

45 The said elastic band can be produced of any material which meets the conditions disclosed above. Suitable are, for example, silicon rubber on the basis of dimethyl polysiloxanes, sulfochlorinated polyethylene, e.g., the product marketed under the trade name "Hypalon," furthermore copolymers of ethylene and vinylacetate as described for example in the French patent specification 1,121,994 or the British patent specifications 843,974 and 853,640, or certain products of the butyl rubber or nitril rubber series.

The band 2 is carried by three rollers 3a, 3b and 3c and is so moved by a motor that it runs over the drum 1 in the direction indicated. The band is so guided that the outside surface of the band, which comes into contact with drum 1 and is heated to the reaction temperature, does not come into contact with any other (colder) elements as it runs over the three guide rollers. As a result, after a few revolutions, the surface temperature of the band, at the point of contact between the roller 3a and the drum 1, is only slightly lower (20 to 70° C.) than the temperature of the drum surface. Since the photographic materials 4a and 4b are introduced at this point, there will be the necessary temperature drop across them and, in travelling from the point of insertion between 1 and 3b, they are given the further treatment according to the other conditions required. The temperature of the drum 1, into which an electrical heating arrangement is incorporated, is adjusted so as to be substantially constant, by regulating members which include a fixed rod-

like bimetallic strip 5, which projects axially into the rotatably mounted drum and which assumes, mainly by heat radiation, the temperature of the heated wall of the drum 1.

The roller 3c is so mounted that the mounting may be displaced in the direction indicated by the two arrows and thus the band tension can be adjusted. Since it is desirable for the pressure of the band on the drum at the end of the developing and transfer zone, i.e., the pressure between the drum 1 and roller 3b, to be adjustable, the mounting or bearings of the roller 3b may also be displaced in the direction indicated by the arrow by pressure screws 6 on both bearings.

The support material is moistened by two moistening cylinders 7a and 7b, which are covered with absorbent elastic material and one of which may be immersed in a tank filled with water. The cylinders 7a, 7b are so driven, through gearwheels 8a, 8b, 8c from the roller 3a, that a foil pushed a suitable feeding speed between the moistening cylinders is guided to the inlet position between 3a and 1.

To strip the supporting foils from the drum 1 after they have travelled through the development and transfer zone, a stripper plate 9 is arranged in the position indicated.

We claim:

1. Apparatus for producing photographic images for a heat transfer process from a supported light-sensitive silver halide emulsion layer being image wise exposed, developed and heated while in contact with a supported transfer layer, comprising a rotatable drum disposed for receiving the supported layers with said layers contacting the surface of said drum at a feed portion and leaving the surface of said drum at a discharge portion, moistening means disposed adjacent said feed portion of said drum whereby the layers are passed through said moistening means and on to the surface of said drum, heating means for heating said drum, said drum having a vapor tight and water impervious surface upon which the layers are in contact, a movable endless belt contacting said surface of said drum between said feed portion and said discharge portion whereby said belt and the portion of said surface of said drum contacted by said belt form a heating zone,

said endless belt being of a water-impervious elastic material of low thermal conductivity whereby said heating zone is water impervious, said endless belt having a temperature between 20° and 70° C. lower than said surface of said heating drum, and adjustable guide means maintaining said belt in close contact with said surface of said drum.

5 2. Apparatus according to claim 1 in which stripping means are disposed at said discharge portion of said drum for separating the layers from said drum.

10 3. Apparatus according to claim 1, in which said heating means includes a fixed bimetallic rod projecting axially into the rotatably mounted drum.

15 4. Apparatus according to claim 1, in which the moistening means consists of two moistening rollers positioned on opposite sides of and disposed for contacting said layers with the centers of said rollers substantially aligned with the point of contact of said rollers and said layers whereby said layers are simultaneously moistened by pressure from one side.
